PANEL ASSEMBLY

Walden E. Reed, Crozet, Va., assignor to Acme Visible Records, Inc., Chicago, Ill., a corporation of Delaware

Application April 11, 1955, Serial No. 500,368

1 Claim. (Cl. 40—102)

This invention relates to a displaceable panel assembly wherein one or more panels or frames are pivotally or swingably mounted in a holder.

It is a particular object to provide an assembly of the class described wherein the panels are securely engaged to the holder and may be quickly and conveniently disengaged therefrom or replaced therein with a minimum of manipulation or moving parts.

The present invention is particularly adapted for use in visible record or index devices where quick and ready access is desired to indicia supported by the opposed faces of a panel or to expose the face of one panel covered in part by another, and where it is desirable to remove or replace the panels as a whole from time to time.

Other objects, advantages, and economies of my invention, together with the details of construction and arrangement of parts thereof will be apparent from a consideration of the following specification and accompanying drawing which, for the purpose of illustration, shows my invention as applied to a specific form of visible index device, and wherein:

Fig. 1 is a plan view of a visible index device embodying my invention.

Fig. 2 is a side elevational view of the device of Fig. 1, with several of the pivotally engaged panels thereof in elevated position.

Fig. 3 is a fragmentary sectional view on the line 3—3 of Fig. 2.

Referring to the drawings, the reference numeral 10 indicates the supporting base of a visible index unit normally adapted to rest on a horizontal surface. Secured to and extending vertically from one end of the base are a pair of spaced, parallel, rigid side walls or brackets 11 and 12, each formed with a series of opposed apertures 13 and 14. Endwise disposed between the brackets 11 and 12 are a plurality of index panel structures 15 arranged on the base in plane parallel relationship thereto, and in stepped relationship thereto. Each of these panels carry a pair of opposed laterally projecting pintles 16 and 17 at one end, these pintles being journaled respectively in the apertures 13 and 14 of the brackets, so as to swingably engage the panels thereto; it being understood that the apertures 13 and 14 in the brackets are spaced so as to permit pivotal movement of one panel with respect to the other in desired relationship, i. e., the previously indicated step relationship.

The specifically illustrated stepped relationship of the panel 15, whereby a lowermost indicia-bearing index strip 20 is exposed free of concealment by the lower edge of an upper adjacent panel to thereby provide a self-indexing device, is more particularly described and claimed in copending application of Oliver K. King, Serial No. 500,518, filed April 11, 1955.

The panels 15, as illustrated, comprise a rigid frame structure provided with longitudinal flanges 18—18 spaced from one or more base plates 19 for endwise reception 20 on one or both of the exposed faces of the panel

2

structure 15. Although the pintles 16 and 17 may be separate, they are a conveniently unitary extension of a rod, embraced and locked against rotation or lateral movement within the bead 21 on the upper edge of the panel structure 15.

The pindle 17 is shorter than the pindle 16, and in the illustration the pindle 17 has a length substantially equal to the thickness of the bracket 12 in which it is received, and the pindle 16 has a length at least substantially equal to the thickness of the bracket 11 in which it is received plus the length of the pindle 17. The width of the panel end disposed between the brackets 11 and 12 is smaller than the distance between the brackets by an amount at least equal to the length of the pindle 17, so that in the absence of a member 22, which will be hereinafter explained, when a panel 15 is laterally moved with one side edge into abutment with bracket 12, its pintles 16 and 17 will be snugly received in the apertures of their respective brackets; but when a panel is displaced into abutment with bracket 11, pindle 17 will drop from aperture 14 in bracket 12, and by slight canting of the panel 15 and movement thereof again in the direction of the bracket 12, pindle 16 will be withdrawn from its aperture 13 in bracket 11.

In operative use and in accordance with the present invention, I dispose flexible resilient cushioning means, such as a strip of rubber 22, between the bracket 11 and the adjacent embraced panel ends, so as to yieldably urge the panels 15 against the bracket 12, and their pintles 17 into seated engagement in their apertures 14 in bracket 12, to thereby hold the panels 15 in yieldably displaceable engagement, with the opposed pintles thereof firmly seated in their respective bracket apertures in secure pivotal engagement until such time as it is desired to positively replace a panel. This is simply and readily accomplished by grasping an engaged panel and urging it toward the bracket 11 against the resiliency of the strip or cushioning pad 22, as illustrated in the section of Fig. 3, to the extent that pindle 17 becomes disengaged from its aperture 14 in bracket 12, and thereafter by slight canting of the panel the pindle 16 may be withdrawn from its aperture 13 in bracket 11, all without disturbing the condition of adjacent panels. In re-engaging the panel, pindle 16 is first inserted into aperture 13 in bracket 11, the panel end bodily urged against pad 22 to locally compress it to the extent that pindle 17 can then be passed into an aperture 14 in bracket 12, and upon release the cushion 22 yieldably urges the panel 15 into abutment against bracket 12 and operative position in a quick and convenient manner.

As illustrated, the flexible, resilient cushioning pad 22 is preferably in the form of a unitary elongated strip secured, as by adhesive means, to bracket 11, and overlying or embracing the apertures 13 thereof, the pad being formed with a series of aligned apertures, so that in practice the pintles 16 when inserted in their apertures 13 in bracket 11 first pass through the aligned apertures 23 in pad 22. It will be understood that as nonfully equivalent alternatives, the pad 22, when apertured, need not be secured to the bracket 11, and may comprise separate or annular units embracing each pindle 16. As a further alternative, pad 22 when secured to bracket 11 may be comprised of a continuous or discontinuous cushioning strip positioned closely adjacent to the aperture 13 in bracket 11.

It will be further understood that although I have described my invention with respect to a visible index device adapted to be supported on a horizontal base with the panels 15 in plane parallel relationship thereto when at rest and in stepped relationship thereto, my invention is also applicable to other related arrangements not illustrated; such as, for example, wherein a pair of similar

3

brackets 11 and 12 project from a base forming a back of a book, with the apertures in the brackets in arcuate arrangement, in which case the bracket 12 would normally be the lower edge, and the cushioning pad 22 adjacent the bracket 11 at the upper edge of the book.

Similarly, although not illustrated, my invention may be employed with vertical stands swingably supporting a plurality of index panels or other frame structures wherein the base is a vertical support having secured at the top and bottom thereof spaced, circular, parallel brackets formed with circumferentially disposed apertures for reception of the panel pintles and in such case the cushioning pad would be likewise disposed or secured adjacent the upper bracket, all similar to the illustration of Fig. 3 when viewed in an inverted position.

It will therefore be understood that various modifications may be made in the details of my invention and its parts without departing from the spirit thereof, as more particularly comprehended by the following claim.

I claim:

In a visible index device, a pivotally supported displaceable panel assembly comprising a base, a pair of spaced parallel brackets projecting normally therefrom each formed with a plurality of opposed apertures, a plurality of index panel structures endwise disposed between said

20

brackets arranged in stepped relationship on said base, a pair of oppositely laterally projecting pintles carried by each of said panel ends and journaled in said bracket apertures swingably engaging said panels thereto, one of said pinte pairs being shorter than the other and the width of said panel ends disposed between said brackets being smaller than the distance between said panels by an amount at least equal to the length of the shorter pinte, and an apertured resilient cushioning strip receiving said pintles and disposed between the bracket and the panel ends carrying the longer pinte yieldably urging said shorter pintles into seated engagement in their holder bracket and the panels in abutment thereagainst, said panels being separately yieldably displaceable against said resilient strip to first disengage the shorter pintles from their bracket and to thereby subsequently permit withdrawal of the longer pintles from engagement with their bracket and the resilient strip.
